VERTICALLY SLIDING FLEXIBLE DOOR

Louis Delivuk, Spokane, Wash.

Application February 17, 1947, Serial No. 729,131

3 Claims. (Cl. 160—133)

1

The present invention relates to the general class of doors or closures, and more specifically to an improved vertically sliding flexible door adapted to be wound upon and unwound from an overhead rotary drum that is electrically operated by a motor and automatically controlled in its operations.

The primary object of the invention is the provision of a closure having these characteristics that is composed of a minimum number of parts which may with facility be manufactured and assembled with convenience for installation to provide a quick-acting and smoothly operating closure.

While the door of my invention is well adapted for various uses, it is especially designed and adapted for use in grain elevators having scale rooms, and scales upon which the grain laden trucks are weighed. Such rooms are usually open at both the front and rear, and wind currents through the room frequently interfere with accurate weighing of the contents of a truck. By the utilization of the door or closure of my invention at the entrance to the room, the air currents may be cut off at the rear of the grain truck, and the truck after weighing may be driven out of the scale room without undue delay.

The invention consists essentially in certain novel features of construction and combinations and arrangements of parts as will hereinafter be described, and more particularly pointed out in the appended claims.

In the accompanying drawings I have illustrated one complete example of a physical embodiment of my invention wherein the parts are combined and arranged in accord with one mode I have devised for the practical application of the principles of my invention. It will however be understood that changes and alterations are contemplated and may be made in these exemplifying drawings and mechanical structures, within the scope of my claims, without departing from the principles of the invention.

Figure 1 is a view in front elevation of a building structure having an opening that is closed by a flexible door in which my invention is embodied, part of the structure being broken away for convenience in illustrating the motor and accessories.

Fig. 2 is an enlarged horizontal transverse sectional view at line 2—2 of Fig. 1 through one of the side columns of the doorway.

Figure 3 is an enlarged, vertical sectional view at line 3—3 of Fig. 1.

Fig. 4 is a detail view in elevation showing the relation of the motor, the rotary winding drum and the flexible slatted door.

2

Figure 5 is a view in elevation and partly in section showing the brake or stop mechanism, and electrical control switches for the door.

Figure 6 is a detail of the wiring or motor circuit with its up and down switches manually controlled, together with the automatically operating electrical devices.

In order that the general arrangement and utility of parts may readily be understood I have shown in Fig. 1 a conventional building structure B which may be the scale room for a grain elevator, and which is provided with a doorway or opening D that is to be opened and closed by the use of the door of my invention. The framing 10 around the doorway includes upright channel plates 1 and 2 at opposite sides of the doorway, and a horizontal channel beam or lintel 3 across the top of the structure. The frame parts 1 and 2 form side columns each having face plates 4 and 5 that are bolted, welded, or otherwise secured, as parts of the columns to provide two vertical guide slots or channels 6.

The flexible, sectional, slatted door is built upon a web, curtain, sheet or screen 7 of heavy textile material or other suitable flexible material that is anchored at one end to an overhead, rotary drum 8 having a horizontal shaft 9 journaled in bearings 10, and the drum is driven by a reversible electrical motor 11 through suitable transmission gearing in the gear box 12, all mounted on a horizontal beam 13 supported at the upper end of an upright frame member 14.

The horizontal slats of sheet metal, or other suitable materials are each made up of an outer horizontal plate 15 and an inner complementary plate 16, which are riveted together at 17, at opposite sides of the central curtain or screen 7, and the curtain between slats forms flexible joints so that the flexible door may be wound upon and unwound from the overhead drum when the latter is operated by the motor.

Each of the outer plates of the slats is reinforced by an exterior horizontal hollow bead 18, and interior strengthening ribs 19 are welded 45 within the bead to the plate to form a strong and rigid slat.

In its vertical movements the flexible door is guided by means of flanged rollers 20 journaled on stud axles 21 projecting laterally from opposite sides of the door, and these axles, are cut-away longitudinally at their inner ends and the inner plates 16 are also cut-away to permit welding of the axles to the door slats, as best seen in Fig. 2.

In Fig. 5 it will be seen that the top slat of the door is equipped with a special pair of axles 22,

and the lower slat at its opposite ends is equipped with a pair of special axles 23, that project through and beyond the guide channels or slots in the upright columns of the door frame.

An inverted channel beam 24 in Fig. 5 is utilized as a sill or base for the door frame, and an upright channel 1 is secured thereto to provide a supporting frame for the electric contacts, a pair of friction brakes or stops, and a pair of spring projected and electrically retracted latches for the door.

For braking and stopping the upward and downward movements of the flexible door, a pair of bowed leaf springs 26 are attached at 27 to the supporting structure 1 and these spring blades are located in the path of movement of the extended axles 22 and 23, which ride in frictional contact with the bowed springs, to retard and stop the movement of the door.

The door is retained in closed position of Fig. 1 by two spring projected latches 28 mounted in the supporting channels 1 and 2 at opposite sides of the door opening in the path of travel of the axle 23, and these latches are retracted by electro-magnets or solenoids 29 when the latter are energized, by closing the up-switch 30 in Fig. 6 to close the circuit for motor 11, which circuit includes a relay 31.

Under power from the motor 11 the unlatched door is elevated or lifted vertically as it is wound upon the overhead drum until axle 23 contacts with a spring projected cam 32 mounted near the top of the door frame, and the cam by its movement opens a closed switch 33 in box 34 to break the motor circuit and cut out the motor 11 and release the relay 31.

For lowering the door the down-switch 35 is pressed to reverse the operation of the motor 11, and current then passes from the switch to the motor, thence to the lower control switch 36 that is operated by a cam block 37 located in the path of the descending axle 23, and through reversing relay 38.

The weight of the lower end of the door assists in lowering the flexible door, and as axles 23 slide past the latches 28 they are pushed back, but the latches rebound to closed position under spring pressure. Near the end of the closing movement of the door axles 23 contact with cam block 37 to open switch 36, release relay 14, and break the motor circuit, to stop the motor, at which time axles 22 contact bowed leaf springs 26, thus stopping the downward motion of the door.

Having thus fully described my invention, what I claim as new and desire to secure by Letters Patent is:

1. The combination with a door frame including laterally spaced vertically slotted columns, an overhead rotary drum, and a reversible motor for operating the drum, of a flexible, sectional door attached at one end to the drum, laterally projecting axles mounted on the door, guide rollers mounted on the axles for co-action with the slotted columns, and resilient means mounted at the tops of the columns forming friction brakes in the path of movement of the axles.
- 15 2. The combination with a door frame including laterally spaced vertically slotted columns, an overhead drum, and a reversible motor for operating the drum, of a flexible door having cross slats and attached at one end to the drum, laterally projecting axles mounted on the slats and guide rollers journaled on the axles co-acting with the slotted columns, and a pair of bowed leaf springs mounted as friction brakes at the tops of the columns in the path of movement of some of the axles.
- 20 3. The combination with a door frame including laterally spaced vertically slotted columns, an overhead rotary drum, and a flexible door windable on and unwindable from the drum, of stud axles projected from the door and rollers thereon co-acting with the slotted columns, an electric motor for operating the drum and a reversible circuit for the motor, electrical control mechanism for the motor mounted in the columns in the path of said axles, a pair of spring-projected latches mounted in the columns for co-action with the door, and electro-magnetic means in the circuit for retracting the latches.

LOUIS DELIVUK.
